OIL WELL PUMPING ASSEMBLY

Paul E. Lehr, Brea, Calif., assignor to Shell Development Company, San Francisco, Calif., a corporation of Delaware

Application August 9, 1948, Serial No. 43,321

7 Claims. (Cl. 103—181)

1
This invention relates to the art of producing hydrocarbon materials from underground formations, and pertains more particularly to an improved oil well pump adapted to be actuated by the reciprocation of a tubing string, said pump being also adapted to be readily positioned in or removed from the well within the tubing string.

Conventional oil well pumps are usually installed at the lower end of a tubing or flow string within the well casing and are operated by reciprocating a string of sucker rods within the tubing. The pump plunger is reciprocated through the sucker rod string by suitable prime mover means at the surface. The sucker rod string is furthermore used, in a well known fashion, to install and withdraw the plunger and traveling valves of the pump. However, in order to remove the entire pump it is necessary to withdraw from the well the entire tubing string to which the pump jacket is attached. Another type of pump, known as an insert pump, can be changed by means of pulling the sucker rod string.

A modification of this system is to be found in the so-called casing pump, wherein the pump is anchored directly in the well casing at the desired depth with sucker rods reciprocating directly within the casing, the tubing string being eliminated. The casing pump depends for its operativeness on the feature of packing off the casing above the pump, whereby the casing itself serves as a tubing string. This type of pump, being secured to the lower end of the sucker rod string, necessitates the removal of the entire sucker rod string whenever the pump is to be raised for inspection or changing.

It is, therefore, a primary object of this invention to provide an improved and simplified pump installation for a well wherein the sucker rod string is eliminated and the pump is installed in the well and reciprocated during operation by the tubing string; said pump being adapted to be readily positioned in or removed from the well by means of a wire line or cable.

It is also an object of the present invention to provide novel means for anchoring a well pump of the traveling barrel type at the bottom of a tubing string within the well, whereby said tubing string is adapted to reciprocate the traveling valve of the pump during operation and is utilized in detaching the pump from its anchored position in the well for easy withdrawal therefrom.

These and other objects of this invention will be understood from the following description

2
taken with reference to the attached drawing, wherein:

Figure 1 is a vertical view, partly in cross section, showing the pump of the present invention anchored in a well.

Figure 2 is a vertical view, partly in cross section, showing the pump being detached from its anchored position within the well.

Figures 3, 4 and 5 are diagrammatic views, partly in cross section, illustrating the method of removing a pump from a well according to the present invention.

Figure 6 is a detail view, partly in cross section, of another embodiment of a means for anchoring a well pump within a tubing string.

Figure 7 is a vertical view, partly in cross section, of another embodiment of a means for positioning a pump anchoring assembly with a well casing.

Figure 8 is a vertical view, partly in cross section, of a detailed view of one embodiment of latching means affixed to the traveling barrel of a pump.

Referring to Figure 1 of the drawing, the pump 25 of the present invention is shown as being positioned in a well having a casing 11 and a casing head 12, provided with suitable conduit connections 13 for the removal of fluids entering the casing in the well. The pump, of a size adapted to be passed through the tubing string, is removably positioned at the lower end of a tubing string 14 which passes into the casing 11 through a suitable lubricator or packing gland device 15. The tubing string 14 serves as means for imparting a reciprocating motion to the pump, as will be described hereinbelow, and is for this purpose connected at 16 to a cable 17 or similar means leading to prime mover means, not shown. The tubing string 14 also serves as a flow or education tube for the oil being pumped, and is connected, through a swivel head 18 to an output conduit 19.

Threadedly secured to the bottom of the tubing string 14, by means of a collar or coupling 20 and a reducer or swaged section of tubing 21, is a shoe assembly which consists of an upper half shoe 22 and a lower half shoe 23 threadedly connected and fixedly securing therebetween a lock seat 24. Affixed to the lower half shoe 23 in any suitable manner, or integrally formed therewith, is a radially extending guide flange 25 having passage means 26 to permit fluid flow therethrough. The lower portion of the lower half shoe 23 is beveled or tapered to form a wedge-shaped latch or lock spreader 27 having, if de-

sired, fluid ports 28 radially extending therethrough. In another embodiment, as shown in Figure 8, the lock seat 24 may be secured in any suitable manner, as by screw threads, within the lower end of the tubing string 14. In a like manner the lock spreader 27 may also be affixed to the lower end of the tubing string 14.

Fixedly anchored at a pre-determined level within the casing 11, by means of any suitable anchoring means such as a tubing catcher 29, is a pump latching means which comprises flexible lock or anchor prongs 30 affixed to a tubular body 31 by any suitable means as by a bushing or holding ring 32. If desired, the holding ring may be a tubular element of a predetermined height, as shown in Figure 1, which thus serves as spacer means for limiting the downward motion of the lock spreader 27. The tubular body 31 is threadedly connected in turn by means of a reducer coupling 33 to a section of tubing 34 carrying the tubing catcher 29. If desired, a tubular guide member 51 of predetermined height may be affixed to the upper end of the body 31 surrounding the latch prongs 30 and serving as guide means for the lower end of the tubing string 14 and the shoe assembly carried thereon. If a gas anchor 35 having fluid inlets 53 therein is to be used, it may be conveniently attached in any suitable manner to the lower side of the tubing catcher 29, as shown in Figure 3. The tubing catcher 29 is normally equipped with conduit or channel means 36 between the slips 52 of the catcher 29 which permit formation gases or fluids to move past the tubing catcher and rise to the surface in the annular space 37 between the well casing 11 and the tubing string 14.

Adapted to be seated on the lock seat 24 of the shoe assembly at the bottom of the tubing string 14 is a well pump of the traveling-barrel type comprising a traveling barrel 38 carrying a ball-type traveling valve 39 and a tubular standing piston or plunger 40 having positioned therein a standing valve 41. Affixed to the lower end of the traveling barrel 38 is a suitable latching means such as a bottom lock hold-down assembly comprising a hold-down body 42 and a seat 43 affixed to or integrally formed with an adapter 44 as shown in Figure 8. A hold-down body 42 generally comprises a short tubular member 57 having a flange 58 formed on the outside surface and at one end thereof. A plurality of longitudinal slots 59 are cut or formed in the wall of the tubular member, extending from the flanged end for a substantial length of the member 57, to divide one end of the tubular member 57 into a plurality of flexible segments 60. The flexible segments 60 are spaced from the adapter 44, as shown in Figure 8, thus permitting them to flex inwardly when the flange 58 is forced past the lock seat 24. On being forced downward the flange 58 springs outward after passing lock seat 24 to secure the pump in the lower end of the tubing string 14. Hence, the hold-down body 42 is adapted to removably position the pump in the lower end of the tubing string 14 so that the seat 43 is in fluid-tight contact with the seat 24 of the shoe assembly thus preventing the leakage of fluid from the tubing back down into the well.

A latching mandrel 45 is fixedly secured to the lower end of the standing barrel or plunger 40 in any suitable manner, as in screw-threaded engagement. The mandrel 45 is of slightly smaller diameter than the lock spreader 27 so as to be able to fit coaxially therein, yet is large enough to contact the hold-down body 42 when the pump is

to be unseated. Fluid ports 46 may be formed in the walls of the mandrel, when a gas anchor is not attached to the pump, to enable fluid from the well to flow into the pump with a minimum of friction. One or more peripheral notches or grooves 47 are cut or formed on the outer wall of the lower end of the mandrel, said grooves being of suitable size and shape to engage and hold anchor prongs 30.

In another embodiment, as shown in Figure 8, one or more peripheral notches or grooves 61 may be cut in the lower end of the tubular standing piston 40 thus eliminating the need of an anchoring mandrel 45 (Figure 1). In order to 10 unseat the traveling barrel 38 of the pump from the lower end of the tubing string 14, a collar 62, pin, or other means is affixed, as by means of a holding screw 63, to the standing piston 40 near the lower end thereof, said collar being of a size 15 to pass within the lock spreader 27 and contact and disengage the hold-down body 42. Instead of employing a collar 62 to unseat the traveling barrel 38, any suitable means may be affixed to or formed on the standing piston 40 forming an 20 enlargement thereon at a point below the normal stroke of the pump during pumping operations.

Pin means 48, of any suitable type, is affixed to the top of the traveling barrel 38 of the pump for removing the pump from the well. In retrieving 25 a pump from a well, a retrieving socket 49 (Figure 5) is lowered into the well on the end of a wire line or cable 50, said socket being adapted to engage and lock onto the pin means 48, whereby the pump may be raised by the wire line. Socket 30 means for positioning or withdrawing tools in well drilling or well maintenance operations are well known to the art and therefore will not be described in greater detail.

In installing the present pump in a well the 35 various elements may be assembled as shown in Figure 1. The traveling barrel 38 carrying the hold-down assembly 42, 43 and 44 at its lower end is secured in the shoe assembly 22, 23 and 24 at the bottom of the tubing string 14 so that 40 the lock seat 24 is in fluid-tight contact with the hold-down seat 43. The grooves 47 on the lower end of the latching mandrel 45, which is 45 attached to the lower end of the standing barrel 40, engage the latching prongs 30 of the pump 50 latching assembly which in turn is threadedly connected to the tubing catcher 29. While running this assembly into the well, the tubing catcher 29 is held in retracted position so as not to engage the well casing 11. When a sufficient 55 number of lengths or sections of tubing 14 have been connected together to lower the pump to its predetermined position in the well, the tubing string is suitably manipulated to set the slips 52 of the tubing catcher 29 against the casing 11 in a manner well known to the art. It is obvious that, instead of lowering the pump latching means 30, 31, 32 and 51 and the tubing catcher 29 by means of the tubing string 14 and pump secured therein, the latching means and tubing catcher may be previously positioned in the well casing by a pipe string or any other suitable means which is withdrawn before the tubing string 14 and pump are installed.

During normal pumping operations, as shown, 60 for example, in Figure 3, the pump, tubing catcher 29 and attached gas anchor 35 are positioned in the producing zone of the well, and the pump is actuated by the tubing string 14 which is reciprocated by the prime mover at the surface 65 (not shown). The fluid enters the gas anchor

38 and passes up into the standing barrel 40 of the pump which remains stationary being anchored in place by the engagement of the anchor prongs 30 and the grooves 47 of the latching mandrel 45. The traveling barrel 38 of the pump, being secured to the lower end of the tubing string 14 by the hold-down body 42, moves in an up and down motion as the tubing string is reciprocated. Thus on the upstroke of the tubing string 14 and traveling barrel 38, the traveling valve 39 is closed and the standing valve 41 is opened allowing fluid to fill the traveling barrel 38 of the pump as the standing barrel or plunger 48 is withdrawn therefrom. In the downstroke of the tubing string 14 and the traveling barrel 38, the standing valve 41 is closed and the traveling valve 39 is opened as the fluid is forced out of the pump by the entering standing barrel 40 which operates as a plunger or piston.

When it is desired to remove the pump from the well, the tubing string 14 and pump elements attached thereto are lowered a distance below the extreme point of its normal downward stroke during pumping operations thus permitting the hold-down body 42 to contact the top of the fixed latching mandrel 45. Further lowering of the tubing string will unseat the pump from the seat of the shoe assembly as the mandrel 45 (Figure 1), or collar 62 (Figure 8), causes the hold-down body to disengage the shoe assembly thus forcing the pump up into the tubing string 14. With the traveling barrel 38 of the pump unseated, the fluid that fills the tubing string 14 is permitted to flow between the traveling barrel and tubing into the well. It is desirable that the head of fluid be bled out of the tubing string to facilitate the removal of the pump.

Continued lowering of the tubing string causes the lock spreader 27 to force the latching prongs 30 outward so as to disengage the grooves 47 of the latching mandrel 45 on the bottom of the standing barrel 40, as shown in Figure 2. The pump may then be removed from the well by lowering a socket 49 on the end of a wire line 50 which is adapted to engage the pin means 48 at the top of the pump.

It is evident that a reversal of the above-described operations may be followed when anchoring and seating a pump in well casing and tubing, respectively. The tubing string 14 may be left in its lowered position when a pump is removed whereby the latch prongs 30 remain in an open position until a new pump is run into the well.

The pump is then lowered within the tubing string by means of a wire line 50 having a socket attached thereto. Such a socket may conveniently be of a type adapted to disengage the pin means 48 by jarring, as known in the art. After the pump has been lowered, the tubing string 14 is raised slightly allowing the latch prongs 30 to engage the grooves of the latching mandrel 45, thus fixedly positioning the standing barrel 40 of the pump. The tubing string is then raised until the hold-down body 42 on the bottom of the traveling barrel 38 locks in the shoe assembly and the seats 24 and 43 are in face to face contact. The pump is now in position to be operated.

While the pump of the present invention has been described as incorporating preferred mechanical bottom lock hold-down assembly 42, 43 and 44 for holding the bottom of the traveling barrel 38 in position and forming a seal to prevent fluid leakage from the tubing string back

into the well, it is evident that any other type of suitable latching mechanism may be used such as, for example, a cup or ring-type hold-down which has been found to be satisfactory in shallow wells (up to 4000 ft.) and at relatively low temperatures (up to 150° F.). As shown in Figure 6, a cup-type hold-down may comprise one or more packer elements 54 carried on the outer surface of the adapter 44 or any other portion of the traveling barrel 38. The packer elements 54 may be made of synthetic rubber, rubberized canvas, or any composition material that is not damaged by the fluid being pumped. The packer elements 54 are of such a size as to anchor the traveling barrel 38 of the pump to the swaged section of tubing 21 at the bottom of the tubing string 14 by a friction contact while being small enough to pass through the tubing string 14. As the tubing string 14 fills with fluid, the head of fluid above the pump also aids in maintaining the pump in a securely seated position.

While the anchoring means may normally comprise a removable tubing catcher 29 as shown in Figure 1, the latching means may also be fixedly positioned in a well in any other suitable manner. For example, such means may comprise a spider 56 disposed at the top of a well screen 55 at the bottom of the casing 11 when the well is completed in this manner as shown in Figure 7. The standing barrel or plunger may be latched to the latching means in the manner previously described.

I claim as my invention:

1. A well pump adapted to be actuated by the reciprocation of a string of tubing comprising, in combination with anchoring means fixedly installed in the well below the lower end of said tubing, a traveling pump barrel releasably latched within the lower end of said tubing, a stationary tubular plunger for said barrel releasably latched to said anchoring means, a standing valve carried by said plunger, and a traveling valve carried by said barrel, whereby well fluid is admitted to said barrel through said tubular plunger and is forced up the tubing by the reciprocating motion of said barrel with regard to said plunger.

2. A well pump adapted to be actuated by the reciprocation of a string of tubing comprising in combination with anchoring means fixedly installed in the well below the lower end of said tubing, a pump barrel inserted within the lower end of said tubing, first yieldable latch means normally locking said barrel with said tubing, a tubular plunger having an upper portion fitting for travel within said barrel and a lower portion having an element of enlarged diameter fitting within said tubing, second yieldable latch means normally locking said plunger with said anchoring means, a standing valve carried by said plunger and a traveling valve carried by said barrel, whereby well fluid is admitted to said barrel through said tubular plunger and is forced up the tubing by the reciprocation of said barrel with regard to said plunger, said first latch means being releasable by the pressure thereagainst of said enlarged element of the stationary plunger occurring upon a lowering of the tubing beyond the extreme point of its normal downward stroke, and said second latch means being releasable by pressure thereagainst of the lower end of the tubing occurring upon a further lowering of the tubing.

3. A well pump adapted to be actuated by the reciprocation of a string of tubing comprising in

combination with anchoring means fixedly installed in the well below the lower end of said tubing, a pump barrel inserted within the lower end of said tubing, first yieldable latch means normally locking said barrel with said tubing, a tubular plunger having an upper portion fitting for travel within said barrel and a lower portion having an element of enlarged diameter fitting within said tubing, second yieldable latch means normally locking said plunger with said anchoring means, a standing valve carried by said plunger and a traveling valve carried by said barrel, whereby well fluid is admitted to said barrel through said tubular plunger and is forced up the tubing by the reciprocation of said barrel with regard to said plunger, said first latch means being releasable by the pressure thereagainst of said enlarged element of the stationary plunger occurring upon a lowering of the tubing beyond the extreme point of its normal downward stroke, said second latch means being releasable by pressure thereagainst of the lower end of the tubing occurring upon a further lowering of the tubing, and lifting means outwardly carried at the top of said barrel, whereby said barrel and plunger can be lifted within said tubing upon release from said first and second latch means.

4. A well pump adapted to be actuated by the reciprocation of a string of tubing having pump seating means secured near the lower end thereof, comprising in combination with anchoring means fixedly installed in the well below the lower end of said tubing, a pump barrel seated within the lower end of said tubing on said pump seating means whereby the lower end of said tubing is closed in a fluid-tight manner, first yieldable latch means normally locking said barrel with said tubing, said latch means being adapted to latch below said seating means, a tubular plunger having an upper portion fitting for travel within said barrel and a lower portion having an element of enlarged diameter fitting within said tubing, second yieldable latch means normally locking said plunger with said anchoring means, a standing valve carried by said plunger and a traveling valve carried by said barrel, whereby well fluid is admitted to said barrel through said tubular plunger and is forced up the tubing by the reciprocation of said barrel with regard to said plunger, said first latch means being releasable by the pressure thereagainst of said enlarged element of the stationary plunger occurring upon a lowering of the tubing beyond the extreme point of its normal downward stroke, said second latch means being releasable by pressure thereagainst of the lower end of the tubing occurring upon a further lowering of the tubing, and a lifting pin outwardly carried at the top of said barrel, whereby said barrel and plunger can be lifted within said tubing upon release from said first and second latch means.

5. A device according to claim 4 wherein said first yieldable latch means comprises a tubular member carried coaxially on said pump, one end of said tubular member being in spaced relationship with said pump, a flange on the outer surface of said end of the tubular member, a plurality of longitudinal slots in said tubular member extending from said flanged end for a distance at least one-half the length of the tubular member, said slots dividing said tubular member into a

plurality of flexible segments adapted to latch below the pump seating means secured to the tubing near the lower end thereof.

6. In a well pumping apparatus adapted to be positioned within a well casing, a string of tubing extending into the well casing said tubing being adapted for reciprocation from the surface, a swaged tubular member of small diameter affixed to the lower end of said tubing, a pump barrel of a size to be passed through said tubing, first yieldable latch means carried by said barrel adapted to engage the swaged tubular member and to anchor and seat said barrel therein, a tubular plunger slidably mounted within said barrel, latch engaging means carried by said plunger, a standing valve carried by said plunger and a traveling valve carried by said barrel, whereby well fluid is admitted to said barrel through said tubular plunger and is forced up the tubing by the reciprocation of the barrel with regard to said plunger, anchoring means fixedly installed at a predetermined level within said well casing below the lower end of said tubing, second latch means affixed to said anchoring means adapted to cooperate with said latch engaging means on said plunger, pin means carried on the top of the pump barrel for lifting the pump barrel and plunger from said tubing, first latch disengaging means carried on the lower portion of said plunger, second latch disengaging means carried at the lower end of said tubing, said first and second latch disengaging means adapted to disengage said first and second latch means whereby said pump barrel and plunger are unseated and may be lifted from the tubing.

7. In a well pumping apparatus adapted to be positioned within a well casing, a string of tubing extending into the well casing said tubing being adapted for reciprocation from the surface, a swaged tubular member of smaller diameter affixed to the lower end of said tubing, a pump barrel of a size to be passed through said tubing, packer elements carried by said barrel adapted to engage the swaged tubular member and to anchor and seat said barrel therein, a tubular plunger slidably mounted within said barrel, latch engaging grooves formed on the lower end of said plunger, a standing valve carried by said plunger and a traveling valve carried by said barrel, whereby well fluid is admitted to said barrel through said tubular plunger and is forced up the tubing by the reciprocation of the barrel with regard to said plunger, anchoring means fixedly installed at a predetermined level within said well casing below the lower end of said tubing, latching prongs affixed to said anchoring means adapted to cooperate with said latch engaging grooves on said plunger, pin means carried on the top of the pump barrel for lifting the pump barrel and plunger from said tubing, a disengaging collar carried on the lower portion of said plunger, an annular latch disengaging wedge carried at the lower end of said tubing, said disengaging collar and wedge adapted to disengage said packer elements and latching prongs whereby said pump barrel and plunger are unseated and may be lifted from the tubing by means of a wire line.
